SHOE

Edward Cohen, New York, N. Y.

Application July 26, 1937, Serial No. 155,671

2 Claims. (CL. 36—17)

This invention relates to shoes and a method of making them.

In general, the object of the invention is to provide a shoe which is of improved construction and appearance and is comfortable when worn.

Another object of the invention is to provide a shoe which has a highly flexible forward portion and yet is of comparatively rugged construction whereby the shoe is well adapted for use as a walking shoe.

A further object of the invention is the provision of a shoe having an upper and a single sole stitched together, except at the heel, in a novel manner whereby to eliminate turning of the upper or the use of separate welt strips or rands.

Another object of the invention is to provide a simple method of making shoes of the character described above.

These objects of the invention and other objects which might hereinafter appear will be fully understood from the following description considered with reference to the accompanying drawing illustrating a preferred embodiment of the invention.

In the drawing:

Fig. 1 is a perspective view of a shoe constructed in accordance with the present invention;

Fig. 2 is a longitudinal sectional view of the shoe, on a larger scale, of the rear part of the shoe;

Fig. 3 is a sectional view on the line 3—3 of Fig. 1;

Figs. 4 and 5 are perspective views of strips of material utilized in making the shoe in accordance with the present invention;

Fig. 6 is a bottom plan view of parts of the shoe assembled on a last, illustrating the method of making the shoe.

Referring to the drawing in detail, the shoe 10 as here shown, is a low shoe and comprises a single sole 12, a heel 14 and an upper 16. As illustrated in Fig. 2, said shoe also comprises a shank piece 18 which extends over and covers the inner surface of sole 12 from substantially the ball line of the shoe to the rear edge of the sole at the heel. Said shank piece includes a metal stiffener 20 and in other respects may be substantially the same as shank pieces commonly utilized in turned shoes for stiffening the shank and heel portions thereof. The usual sock lining 22 is disposed over the shank piece 18. A counter stiffener 24 is also provided in the shoe.

An important feature of the present invention

is the construction of the upper 16 and the manner of attachment thereof with sole 12. Said upper comprises a main part 26 composed of any suitable shoe upper material, such as suede, calfskin, fabric, or combinations of such materials, 5 or any other suitable material utilized for shoe uppers. Said upper also includes a lower marginal part 28 which extends completely around the shoe. Marginal part 28 is composed of sturdy material and is preferably thicker than the material of upper portion 26. For this purpose, I prefer to utilize thin sole leather such as that used as weltling and cut so that the grain side of the leather is retained in the material for disposition on the outer surface of the shoe. 10 Marginal part 28 is constituted by a strip 30 which extends from a point 32 at one side of the shoe, preferably just rearwardly of the heel breast, forwardly around the toe of the shoe, and then rearwardly to a similar point 32 at the 15 other side of the shoe, and by a strip 34 which extends around the heel part of the shoe with its ends in abutting relation to the ends of strip 30. As shown in Figs. 3 and 4, strip 30 is provided with an outwardly directed flange 36, preferably pre-formed, disposed substantially at right angles to the body of the strip. Said flange may be formed in any suitable manner as by a molding operation.

Strips 30 and 34 are secured to upper part 26 in any suitable manner, here shown as double lines of stitching 38 which extend completely around the shoe, said strips being disposed in overlapping relation on the outer surface of the lower marginal edge portion of upper part 26. 35 As shown in Figs. 1 and 2, strip 34 has its lower edge turned inwardly beneath the heel seat and is tacked in position together with counter stiffener 24 to the rear marginal edge portion of shank piece 18. Sole 12 is attached to upper 40 16 and more particularly to the flange 36 of strip 30 by a line of through and through stitching 40, said stitching being co-extensive with strip 30 and extending from point 32 forwardly around the toe of the shoe and then rearwardly to a 45 similar point at the other side of the shoe. The rear portion of sole 12 is subjected to the usual heel seat forming operation and then heel 14 is attached in any suitable manner which need not be specifically described, as it is not per se 50 part of the present invention.

In making a shoe of the present construction, the part 26 of the upper 16 is cut to shape and then strips 30 and 34 are stitched to the lower marginal edge portion of part 26 completely there- 55

- around. In actual practice, strip 30 is pre-formed with its outwardly directed flange 36, and strip 34 is preferably of the desired width whereby to eliminate the necessity for trimming said strip.
- 5 When a counter stiffener is utilized, said stiffener is stitched to the upper. Then, as shown in Fig. 6, the upper is assembled on a last L together with the shank piece 18 and its metal stiffener 20, and the outer marginal edge portion of strip 34
- 10 is inturned in overlying relation to said shank piece together with the inturned edge portion of counter 24 and are secured to said shank piece in any suitable manner as by tacks 42, the ends of which are clinched against the last bottom.
- 15 The forward part of the upper is held against the sides of the last with the flange 36 of strip 30 substantially flush with the bottom of the last. Then the sole 12 is laid over the bottom of the last and cemented to the surface of flange 36 and
- 20 if preferred said sole may also be cemented to the surface of shank piece 18. After the cement has set sufficiently to retain the parts in position said sole is stitched to flange 36 while the parts are on the last. Then the heel seat is formed at the
- 25 rear part of the sole, and heel 14 is attached in the usual way. The last is then removed and the shoe is then subjected to a re-lasting operation, such as that employed in making turned shoes. For this purpose, there is utilized a last somewhat
- 30 larger than the last used in the first lasting operation. In re-lasting the shoe, the upper is shaped to the last and the upper is treated in accordance with the usual process of re-lasting shoes to smoothen the upper, remove wrinkles,
- 35 etc. After the re-lasting operation the shoe may be completed in the usual way.

Thus, it is seen that the construction and method herein disclosed are well adapted to accomplish the several objects of the present invention. While the present shoe is illustrated as a lady's shoe, the invention may be utilized in connection with other shoes. It will be understood that certain changes in the construction and method will occur to those skilled in the art in view of the present disclosure. For example, the shoe may be a high shoe instead of a low shoe and instead of utilizing a shank piece extending to the ball line of the shoe, as in a turned shoe, I may utilize instead a heel piece which covers

40 substantially the heel portion of the sole on the inner surface thereof and is sufficiently large to secure thereto strip 34 and counter 24, but does not extend a substantial distance forwardly of the heel breast. Other variations in the construc-

tion may be made. It will also be understood that unless otherwise specified, the steps of the method need not be performed precisely in the order in which they are recited, and that unless otherwise specified one or more steps may be performed without the others or with the equivalent of the specific steps which may be omitted. Finally, it is to be understood that the present invention is not to be limited by the preceding specific disclosure as to the construction of the 10 shoe or the method of making the same, except as may be required by the appended claims considered with reference to the prior art.

Having thus described my invention, what I claim and desire to secure by Letters Patent is:

1. A shoe comprising an upper, a sole, a shank piece, and a heel, said upper having a main part extending downwardly from the foot opening and terminating inwardly of the outer edge of said sole, and a lower marginal part including a forward strip portion extending from the rear part of the shoe at one side thereof forwardly around the toe and rearwardly to the rear part of the shoe at its other side, said strip portion being composed of welting material and having its upper 23 edge stitched to said main upper part above said sole and having a lower out-turned edge portion stitched to the marginal edge of said sole, outwardly of the adjacent edge of said main upper part, and a rear strip portion of welting mate- 30 rial stitched to the main upper part and inturned and secured to said shank piece at the heel seat.

2. A shoe comprising an upper, a sole, and a heel, said upper having a main part extending downwardly from the foot opening and terminat- 35 ing above said sole inwardly of the outer sole edge, and a lower marginal part including a forward strip portion extending from the rear part of the shoe at one side thereof forwardly around the toe and rearwardly to the rear part of the shoe 40 at its other side, said strip portion being thicker than the material of said main upper part and having its upper edge stitched to said main upper part above said sole and having an out-turned edge portion stitched to the marginal edge of said 45 sole outwardly beyond the adjacent edge of the upper, and a rear strip portion extending between the ends of said front strip portion around the heel part of the shoe, said rear strip portion being thicker than the material of said main upper 50 part and attached to said main part and having a lower inturned portion secured in position at the heel seat.

EDWARD COHEN.
